UNITED STATES PATENT OFFICE.

BARNABAS BRYAN, OF WASHINGTON, DISTRICT OF COLUMBIA.

SEALING-WAX-APPLYING DEVICE.

1,109,034.

Specification of Letters Patent. Patented Sept. 1, 1914.

Application filed June 17, 1912. Serial No. 794,058.

To all whom it may concern:

Be it known that I, BARNABAS BRYAN, a citizen of the United States, residing at Washington, in the District of Columbia, have invented certain new and useful Improvements in Sealing-Wax-Applying Devices, of which the following is a specification, reference being had to the accompanying drawings.

10 This invention relates to improvements in devices for melting and applying sealing wax; and an object of this invention is to provide a device of this character which will be simple in construction, comparatively cheap in manufacture and efficient and economical in operation and use.

Another object of this invention is the provision in a device of this character of heating means which will deliver the wax in 20 such a state of plasticity as will render the operation of sealing rapid.

A third object of this invention is the provision of a sealing-wax applying device in which the wax not in the vicinity of the 25 heating elements will be maintained in a cool condition, whereby the instrument will be kept in a clean and unclogged condition ready for immediate service when next required for use.

30 A further object of this invention is to provide a device of the type just mentioned which will be suitable for periods of long continued use and which, therefore, will not absorb and retain heat.

35 A fifth object of this invention is the provision in a device of the class just referred to of means for controlling the heat generated and the concentration thereof upon that portion of the wax which is to be 40 melted for immediate use so as to give the same the required degree of plasticity without producing a too high temperature and a too great softness, both of which latter tend to retard the operation of sealing, particularly where the number of packages to be sealed is large.

45 A sixth object of this invention is so to arrange the heating elements as to permit a free flow of the molten wax therefrom and thereby to increase the rapidity of the operation of sealing.

In the drawings illustrating the principle

of this invention and the best mode now known to me of applying that principle, Figure 1 is an elevation of the instrument, 55 partly in section; Fig. 2 is a section on the line A—A of Fig. 1; Fig. 3 is a section on the line B—B of Fig. 1, looking in the direction of the upper end of the device (or away from the heating elements); Fig. 4 is 60 a section on the same line B—B but looking toward the working end of the device (or toward the heating elements); Fig. 5 is a detail in section showing the interior construction of one of the heating elements; 65 Fig. 6 is a detail showing the manner in which one of the resistance coils of the heating elements is wound; Fig. 7 is a detail showing in elevation one face of the mica casing of the resistance coils; Fig. 8 is 70 a detail showing the opposite side or face of the casing illustrated in Fig. 7; Fig. 9 is a detail showing in perspective the outside sheet-metal housing or cover for the heating element; Fig. 10 is an elevation, partly 75 in section of a modified form of this invention, and Fig. 11 is a plan view of the same.

Similar reference characters designate corresponding parts throughout the several views.

The body portion *a* of the instrument is oval in transverse section (Fig. 2) and is so shaped as to be readily grasped and held in the hand after the manner of a handle. For making this body portion *a*, there should 85 be used a material which is a poor conductor of heat (a heat-insulating substance) and at the same time a bad conductor of electricity (electric insulator). The patented substance which is commercially 90 known as "bakelite" has been found by me to serve this purpose well. The body portion *a* is formed with a central longitudinal bore *b* which is of suitable section (that is, suitably shaped) to receive a stick of sealing wax 20. The upper end of this centrally-disposed bore *b* may be closed by a spring-held cap *d*. At each side of the tubular bore *b* there is formed in the body *a* a lengthwise-extending passage or channel 100 *e* through which passes one of the lead wires *f* from a suitable source of electric current (not shown).

From the working or lower end of the

body *a* there projects a pair of arms *g* which are preferably formed integral therewith and which lie on opposite sides of the longitudinal axis of the instrument. These arms 5 *g* converge toward each other and serve to support the stick of sealing wax 20. Each of these arms carries on its inner face a heating element *h*; and, since the construction of these heating elements *h* is the same, 10 a description of one of them will suffice as a description of both: Upon a strip *i* of suitable insulating material (such as mica) is coiled resistance wire *j* (such as the wire known in the trade as nichrome wire); and in 15 the ordinary size of the commercial instrument, each resistance coil *j* contains about six or seven feet of No. 38 nichrome wire, where the electric circuit is operated under an electrical pressure of 110 volts. The 20 mica strips *i* are formed with holes *i'* at their ends, through which holes are passed the ends of the resistance-wire coil *j*. The mica strip *i* is then folded or doubled on itself along its midline *i''*. Between the two 25 heating coils *j* is interposed a layer of mica *k* which serves to insulate the coils *j* which have been thus brought adjacent to each other (Fig. 5). The heating coils *j* and the interposed insulating strip *k* are next in 30 closed within an insulating casing, such as the mica casing *n*, one face *n'* (Fig. 8) of which is formed with a hole *n^x* through which is passed one end of the resistance-coil wire *j*, which is then attached to a suitable 35 piece of lamp-cord forming one of the lead wires *f*. The other end of the resistance-coil wire is electrically connected with the metal contact-plate *o* with which the other face *n''* of the mica casing *n* is provided. The heating element or heater *h* is 40 inclosed within and held in place by means of a sheet-metal boxing or casing *p*. The upper edge portions of the sides *p^x* of this sheet-metal box or cover *p* are folded in 45 toward each other and are firmly engaged with the sides of the arms *g*. The lower end *p''* of the sheet-metal boxing is hook-shaped and incloses the outer or lower end of the arm *g*. The contact strip *o* is held in good 50 electrical contact with the face *p'* of the cover *p* and the latter is secured to the upper end of the arm *g* by means of screws *q* which pass through the holes *q'* formed in the upper part of the face *p'*. These screws 55 *q* fasten in place also the lower edge portion of a ferrule or contact-ring *r* which connects electrically the two housings *p*. This ferrule *r* is located at the outlet end of the wax-containing bore *b*; but it is made so 60 light that it absorbs only little heat and transmits no heat to the wax. If desired, it may be placed as an ornamental binding around the outside of the handle. The electrical circuit may now be traced as follows:

from one of the lead wires *f* through the resistance coils *j* of one of the heaters *h*, thence through one of the contact plates *o* and one of the sheet-metal casings *p* to the ferrule *r*; then through the other heater *h* and the other lead wire *f*. 65

The operation of the device is as follows: The wax 20 is inserted in stick or like suitable form in the central passage *b* of the handle *a* and, when the device is held vertically, the stick 20 drops down until its 70 lower end comes in contact with the heating elements *h* which, being inclined toward each other, limit the amount of downward movement of the stick. When the circuit is closed, the wax will be softened at its lower 75 end and can then be applied from the working or melting end of the instrument to the place to be sealed by rubbing this end of the instrument around, the latter being conveniently held in one hand while the other is 80 used to apply the stamp or impression device. Owing to the shape and arrangement of the heaters and the amount of heat generated therein, the device may, without any 85 danger of the wax becoming sufficiently 90 melted to drop from the heaters, be held up from the paper for ample time to permit the application of the stamp and the replacing of the sealed and stamped article by another one to which the wax is to be applied. 95

By making the covers 10 and the ferrule 11 of very light stiff metal they are able to transmit such a small amount of heat up toward the holder that the power can be left 100 on for a very considerable time without any softening of the wax in the holder. Since the section of the device is an oval, as shown at Fig. 2, no soiling and clogging up of the parts occur, even though the device be 105 thoughtlessly dropped and the power be inadvertently left turned on for an indefinite period. This is true because the device will always roll to the position shown in Fig. 2, and the wax that is softened after the device 110 is laid down will flow by gravity down between the heaters and will not clog the holder.

In the case of offices where it is desired to have the wax flow sooner than the heaters 115 *h* will ordinarily soften it, there may be added outside of the device an additional resistance from which the device receives a small amount of current when the device is not in use, so that the heaters *h* will always 120 be maintained slightly warmed. Then when the full current is made to flow through the heaters *h* and the outside resistance is short-circuited, the wax will be softened and flow in a very few seconds. 125

Where the device is to be used intermittently and yet often enough to make the turning on and off of the current objection-

able, an automatic switch may be added in the form of a hook on which the device is hung, when not in use. This arrangement would be of the ordinary form used in all 5 telephone sets in which the weight of the receiver upon the hook moves the lever to break the circuit, and its removal allows a spring to act to close the circuit. Beneath this hook may be held a small cup to catch 10 any drippings of wax which may fall, after the device is hung up.

In Figs. 10 and 11 there is illustrated a specific embodiment of this modification of the invention. To the bottom of the drip- 15 pan *s* there is suitably fastened, as by the screw *t*, a disk *u* upon which is screwed the lower end of the tubular post *v*, the top of which is closed by the screw-cap *w* formed with a central hole *x*. The tubular post *v* 20 is formed with a hole *y* and a pair of slots *y'*, through which slots extends one end of a switch-arm *z* the other end of which is bifurcated. The switch-arm *z* is fulcrumed at 2 upon the tubular post *v* and 25 is held depressed by the weight of the wax-holder *a* of the device. Above the switch-arm *z* and within the tubular post *v* there is mounted a block *3* of insulation to which is suitably fastened a contact-plate *4* carrying 30 a binding post *5*. The lead wires *f* are passed through the holes *y*, *x*, and one part of one of the lead wires *f* is fastened to the binding post *5*, while the other part of this lead wire is attached at 6 to the switch-arm *z*. A coil-spring *7* is interposed between the post *v* and the switch-arm *z* and tends to 35 pull the latter upwardly into contact with the contact-plate *4*. When the wax-holder *a* of the device is removed from the switch-arm *z*, the spring *7* pulls the latter into contact with the contact-plate *4*, (see dotted line position of Fig. 10), thereby completing 40 the circuit and causing current to flow through the heating elements *h*. By replacing the holder *a* upon the switch-arm *z*, the circuit is broken (see full-line position of Fig. 10).

The spacing of the heaters *h* performs several functions which are essential to the 50 successful operation of a device of this type. The open or air-cooled space about the wax 20 is necessary to keep the same from being softened up to the outlet end of the bore *b* of the holder and to prevent the wax on the 55 surface of the heaters from becoming overheated and running back into the bore of the holder and clogging the latter. The object of the convergence of the heaters *h* is to make it possible to deliver the wax to the 60 spot to be sealed in a condition of plasticity proper for the application of the impression device. By reason of this convergence, the weight of the stick of wax in the holder forces the center of the softened end

through between the heaters *h* in a comparatively hard though plastic condition, so that in rubbing the wax upon the spot to be sealed, the hard portion takes part of the heat of the soft wax which flows down the inner faces of the heaters, whereby the 65 molten mass as a whole, is, as it reaches the paper, of the right plasticity for the application of the stamp. The relation between the width of the stick of wax and the width of opening between the heaters has an important bearing upon this degree of plasticity of the applied wax. 75

I claim:

1. A sealing-wax applying-device including a body portion composed of insulating material and formed with a lengthwise-extending channel for a stick of sealing-wax and at one of its ends with a pair of integral spaced jaws; a pair of electrical heaters carried by the latter and having casings of 80 conducting material which converge toward their outer ends and are arranged to support that end of the stick of sealing-wax which is to be melted; said casings being opposed to each other and spaced apart by 85 lateral openings for the free flow of the melted wax therethrough sidewise of the body portion; that portion of the stick of sealing-wax which lies between the outlet of said channel and said heaters being exposed to air-cooling. 90

2. A sealing-wax-applying device including a body portion which is oval-like in cross-section and is formed with a lengthwise-extending channel for a stick of sealing-wax and which is provided at one end with a pair of spaced electrical heaters which are opposed to each other and separated by integral openings which permit the free flow of the melted wax in a direction 100 substantially parallel to the shorter transverse axis of the body portion, whereby clogging of the outlet end of said channel by back-flowing wax when the device is laid down horizontally is avoided. 105

3. A sealing-wax-applying device including a body-portion composed substantially throughout of a heat-insulating and electric-insulating material and formed with a lengthwise-extending channel for a stick of sealing-wax and with passages for electrical conductors; and electrical heating elements carried by said body portion and provided with casings of conductive material arranged to receive that end of the stick of 115 sealing-wax which is to be melted, said elements being separated from the outlet end of said channel by a substantial air-space which keeps cool that portion of the stick of sealing-wax which lies just beyond the 120 outlet end of said channel. 125

4. A sealing-wax-applying device including a body-portion formed at one end with

1,109,084

a swell and at its other end with a pair of integral spaced jaws; and electrical heating elements carried by the latter.

In testimony whereof I hereunto set my hand at the borough of Manhattan, city, county and State of New York, this fif-

teenth day of June, A. D. 1912, in the presence of the two undersigned witnesses.

BARNABAS BRYAN.
